TENSION CONTROL, STOP MECHANISM, AND
WARNING SIGNAL FOR KNITTING MA-
CHINES

Robert N. Ambler, Indianapolis, Ind.

Application July 3, 1944, Serial No. 543,248

17 Claims. (Cl. 66—163)

This invention relates to improvements in tension control and stop mechanisms for knitting machines, coning machines and the like.

It is particularly adapted to equalize tension on yarn, thread, etc., in machines in which the yarn is freely fed to the machine without restraint or restriction at the source of supply, but which encounters in the machines variable factors of demand, such as, for example, are found in the carrier arms of hosiery knitting machines, which in travelling forward and backward across the needle bars subject the yarn to a constantly varying rate of travel and consequent varying tension.

This invention is also particularly adapted to stop the knitting machine should the yarn or thread be broken at any point, should it develop a knot or slub such as would break the thread in its travel through the machine, or should any factor develop a tension on the thread either greater or less than the predetermined limits imposed by the initial adjustment of the device.

It is likewise particularly adapted to energize a warning signal such as to light a warning lamp or ring a warning bell, and at the instant the machine is stopped by reason of a thread break, run out, or increased tension, etc. Such signal may be individualized to enable the operator of the machine to locate promptly the source of trouble by individually indicating the thread which has caused the stoppage.

Other advantages and novel features of the invention will be set forth more fully in the specification.

The full nature of the invention will be understood from the accompanying drawing and the following description and claims:

In the drawing:

Fig. 1 is a central section of the essential parts of the device.

Fig. 2 is a perspective view of the device.

Fig. 3 is a wiring diagram of a circuit and in which is included a plurality of the devices and one preferred arrangement of warning signals.

Fig. 4 is a perspective view looking toward the rear of the spindle member, contactors, counter weight and tension arm.

The frame consists of base member 16, upper eyelet supporting tongue 15, side brackets 18, and the window 17 in the base. Brackets 18 carry and support on point bearings 6 the spindle member or spindle 8, which is pivoted on point bearing sockets 5 and moves freely in a vertical plane through an angle of approximately 105°.

Spindle 8 at right angles to its axis carries at the midpoint the pin 20. At the rear side of the spindle 8 and adjustably positioned on the pin 20 is counterbalancing weight 7. On the forward end of pin 20 is affixed the tension arm 4, which is loop shaped at its outer end to hold a porcelain or like eyelet 2. Spindle 8 also carries switch contactors 9 and 10 which selectively meet and contact the flat spring switch blade 12 at the upper and lower limits of movement of the tension arm 4. Same are offset axially relative to pin 20.

In its preferred form a single switch member 12 is employed to energize and thus actuate an electronic relay or the like, which in turn may light a warning lamp and open an electric circuit to the driving motor and its associated dynamic braking mechanism of a machine such as a knitting or coning machine. A second switch blade 12a may be mounted, however on the base member 16 and selectively contact a second pair of contactors 9a and 10a on spindle 8, similar to contactors 9 and 10, should it be desired to separate the warning light function from the stop motion function of the electronic relay. The contactors 9 and 10 and 9a and 10a are each oppositely offset from pin 20.

The switch blade 12 is insulately supported by insulation plate 13 on the base member 16. Switch blade 12a is similarly mounted on the base. Also mounted on said base member 16 is a flat spring 14 with an angular end which extends through the window 17 and normally lies above the counterweight 7. The end 21 of said spring 14 is so positioned that it is engaged by the forward (arm associated) end of pin 20 when the tension arm 4 approaches the upper limit of its movement. Upon such engagement, the spring 14 impedes further arm movement toward said upper limit and such impedance is progressive.

In normal use thread 22 is threaded through porcelain eyelet 1 carried by tongue 15, thence through eyelet 2 on tension arm 4, thence through eyelet 3 in base 16 and thence to the machine upon which the present device is mounted. Thread movement through the eyelets is in the direction shown by the arrows. Said movement is resisted by the friction of eyelets 1 and 2 upon the thread. The amount of frictional resistance for a given type of yarn is proportional to the velocity of thread movement and to the position of the tension arm 4. Since tension arm 4 is free to move in a vertical plane, which is also the plane of the strands of yarn, eyelet 2 is lifted

toward eyelet 3 as the velocity of the movement of the thread is increased, and conversely is lowered again toward its lower position as velocity of movement is decreased. Thus, except in the case of breaks, runouts, or slubs, the position of the tension arm 4 is at all times responsive to variations in the rate of travel of the yarn or thread to the knitting or like machine.

It is to be noted, however, that should a knot or sub develop in the source of supply, or should the thread be broken at any point, then the position of the tension arm 4 is no longer responsive solely to the friction in eyelets 1 and 2, but is also responsive to the undesired change in tension. Should such a change in tension develop at the source of supply, then tension arm 4 drops to its lower limit position in the case of too little tension, or is lifted to the upper limit position if the tension be too great. As the tension arm 4 approaches its upper limit position, its pin 20 engages spring 14 at 21 in such a way that free movement of the said tension arm is impeded slightly, so that switch contact 8 will not immediately contact switch blade 12, except as the tension is such as probably will break the thread if such tension be continued. The foregoing also applies to contact 8a and switch 12a when same are used. Spring 14 is selected and adjusted to accommodate the thread which is being currently used.

The tension arm 4 and counterbalancing weight 7 are so constructed that the moving member is in exact equilibrium when the tension arm 4 is positioned in the same straight line as pin 20 which carries the counterbalancing weight 7 at its opposite end. Adjustable control of tension is secured by bending the tension arm 4 downward, thus moving the center of gravity of the moving system to a position below the points of support, in this case below a horizontal line drawn through point bearings 6. When the thread or yarn is moving through eyelets 1, 2 and 3, as hereinbefore described and in the direction of the arrows, eyelet 2 is lifted toward eyelet 3. Thus the tension arm 4 is a lever system operating about a center of moments at the point bearings 6 and arranged in such manner that the center of gravity of the whole moving system is lifted by the tension arm 4 in its upward movement.

The mechanical advantage of the said lever system is the ratio of the length of the tension arm to the distance to which the center of gravity was lowered by the bending of the tension arm downward as described. Said mechanical advantage is therefore adjustable by the amount of bending of the tension arm, and when once it has been adjusted to provide the desired tension, no further adjustment is necessary. Bending is not the only method of adjustment, but appears to be the easiest.

In the adjustment which has been described it will be observed that as the tension arm 4 is lifted toward eyelet 3, the center of gravity must be lifted, and since the moment of force exerted by said center of gravity is proportional to the sine of the angle of the movement, resistance to movement is least at the lower position and greatest at the upper position of said arm.

It is to be observed likewise that in the manner of threading the yarn through eyelets 1, 2 and 3, two supporting strands of thread, that is one between eyelets 1 and 2 and the other between eyelets 2 and 3, operate to lift tension arm 4. At the lower position, the said two strands are ap-

proximately parallel and the effective resultant of their lifting force is their sum. But as tension arm 4 is moved upward the angle between the two lifting forces is increased, and their effective treatment is reduced.

It will be also observed that the effective lifting component of the force is at right angles to tension arm 4, and that this said effective lifting component of the force is proportional to the sine of the angle through which the tension arm has been moved, increasing as the tension arm approaches its upper position.

Thus the resisting force due to the lifting of the center of gravity increases and the effective component of the lifting force increases in the same proportionate rate so that they are at all times in balance against each other, so that the resultant effect is to produce a constant tension on the yarn, within the limits predetermined by the weight of the moving structure and its adjustment in the manner described.

In Fig. 3 of the drawing there is conventionally illustrated one wiring diagram of the electrical application of the foregoing tension control. It is expressly stated that this illustration is but one of many and is merely the one selected for exemplification.

In said figure 40 indicates a motor terminal, 41 a similar terminal and 42 a dynamic brake terminal. Power lines 43 and 44 have branches 45 and 46, the latter connecting to terminal 40 and the former to terminal 41 by normally closed switch 47 and line 48. Terminal 42 has line 49 connected thereto and switch contact 50.

When switch 47 is closed, the motor is energized. When it is opened, said switch engages contact 50 and energizes the dynamic brake in the well known manner, the braking circuit comprising line 43, line 45, switch 47, line 49, line 46 and line 44. The motor circuit comprises line 43, line 45, switch 47, line 48, line 46 and line 43.

Power lines 43 and 44 are connected to the primary 51 of a power transformer having secondaries 52, 53 and 54. Relay 55 is in series with secondary 54 and plate 56 of tube 57. This tube includes grid 58, cathode 59 and filament 60.

Secondary 52 has line 61 connected to the cathode 59 and filament 60. The latter is connected across secondary 52 by series connected lines 62 and 63. Line 61 is extended at 64 and connected at 65 to a plurality of parallel connected spindles 8. Juxtaposed thereto are the spring contacts 12a and 12, each of the former connecting by a line 66 to signal lamp 67 connected by line 68 to line 63. Thus each tension arm herein has a signal light and same is individual to that arm so the operator can readily locate the thread break, interference, etc., in the machine.

All contacts 12 are connected by line 69 to tap 10 of resistor 71-72, the latter being connected by line 73 to secondary 53. Tap 74 from secondaries 53-54 connects at 75 to line 61. Line 76 from resistor 71 connects to grid 58.

Now when any arm (spindle 8) engages spring 12 adjacent thereto (spindle 8 having upper and lower limit contacts 9 and 10) the tube is energized and relay 55 is energized to open switch 47 to the motor and close switch 41 to the brake.

Thus immediately upon any arm 4 attaining its upper or lower limit the motor is deenergized and the brake applied and the individual warning signal (as indicator or locator) is energized.

An audible signal may be in multiple with each light or preferably a single audible signal 90 may be in multiple with the brake circuit. This calls the attention of the operator, who services many machines, to the occurrence of a failure and in multiple with the audible signal there may also be a light signal 91 to designate the machine which automatically has been stopped. When the operator reaches that machine, the individually energized light 67 will designate the thread which has failed.

The foregoing facilitates location and repair of thread failure and expedites machine reoperation.

While the invention has been illustrated and described in great detail in the drawing and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. A constant tension device suitable for knitting, coning and like machines, having in combination a rocking lever with two arms, one of said arms being longer and having at its end an eyelet for guiding yarn and the other end of said arm being shorter and carrying a counterbalancing weight adjustably positioned thereon, the said entire lever system being pivoted to move freely in a vertical plane about a point of equilibrium, means pivotally supporting said lever, the said long arm being adjustable to provide a change in the position of the center of gravity of the said lever system in a vertical plane including the sweep of said arm, the said center of gravity being lifted by upward movement of said lever and offering constantly increasing resistance to said movement as the angle through which it has moved is increased, a second eyelet positioned substantially in the plane of movement of said lever to guide yarn from a source of supply to the said first eyelet on said long lever arm, and a third eyelet also positioned substantially in the plane of movement of the lever to guide yarn from the said first eyelet to the machine, the said three eyelets being positioned with respect to each other so as to provide friction on the yarn and thereby to provide a constantly increasing effective lifting force on the long arm of said lever.

2. A tension device as defined by claim 1 wherein there is provided resilient means engageable by the lever as the same approaches its upper limit of movement and for progressively impeding further movement toward said upper limit.

3. A constant tension device as defined by claim 1 wherein there is provided a switch juxtaposed to said lever and operated by movement thereof, a suitable source of electric current and a warning lamp connected thereto and controlled by said switch.

4. The structure as defined by claim 1 wherein a switch is mounted with respect to said lever and is operated by movement thereof, a suitable source of electrical supply connected to the switch, an electric motor, and braking means for machine operation and stoppage respectively and connected to said supply, means controlling the latter connection, and means controlled by said switch for actuating said last mentioned means for effecting motor stoppage and braking of the machine.

5. The structure as defined by claim 1 wherein a switch is mounted with respect to said lever and is operated by movement thereof, a suitable source of electrical supply connected to the switch, an electric motor, and braking means for machine operation and stoppage respectively and connected to said supply, means controlling the latter connection, and means controlled by said switch for actuating said last mentioned means for effecting motor stoppage, said first mentioned controlling means including a switch normally biased to motor circuit position and movable by the last mentioned means to motor open circuit and brake closed circuit position.
6. The structure as defined by claim 1 wherein a switch is mounted with respect to said lever and is operated by movement thereof, a suitable source of electrical supply connected to the switch, an electric motor, and braking means for machine operation and stoppage respectively and connected to said supply, means controlling the latter connection, and means controlled by said switch for actuating said last mentioned means for effecting motor stoppage, said first mentioned controlling means including a switch normally biased to motor circuit position and movable by the last mentioned means to motor open circuit and brake closed circuit position, said last mentioned means including a relay.
7. The structure as defined by claim 1 wherein a switch is mounted with respect to said lever and is operated by movement thereof, a suitable source of electrical supply connected to the switch, an electric motor, and braking means for machine operation and stoppage respectively and connected to said supply, means controlling the latter connection, and means controlled by said switch for actuating said last mentioned means for effecting motor stoppage, said first mentioned controlling means including a switch normally biased to motor circuit position and movable by the last mentioned means to motor open circuit and brake closed circuit position, said last mentioned means including a relay of electronic type and an electron tube connected thereto.
8. A constant tension device comprising three substantially coplanar thread guides, two of the guides being comparatively close to each other and the intermediate guide being simultaneously movable toward or away from the same, a pivotally supported, counterbalanced, substantially horizontally directed arm for said intermediate movable guide and beneath the other two guides, said arm moving substantially in the plane of said guides, the direction and extent of the arm movement being proportional to the thread tension, and resilient means operatively engageable by the arm in its guide movement toward the other guides and progressively impeding such arm movement toward said other guides.
9. A tension device as defined by claim 8 wherein there is provided a control switch, and means carried by the arm for operative engagement with the switch when the arm is tilted closest to the said other guides.
10. A tension device as defined by claim 8 wherein there is provided a control switch, and means carried by the arm for operative engagement with the switch when the arm is released from thread tension.
11. A tension device as defined by claim 8 wherein there is provided a control switch, and dual, arcuately spaced means carried by the arm for selective operative engagement with the

switch when the arm is tilted closest to said other guides or when the arm is released from thread tension.

12. In a control system for knitting, coning and like machines having a driving motor and a brake, and switch means differentially controlling same, the combination of a single means controlling said switch means, a plurality of yarn tensioning devices, there being one for each yarn and having a portion movable proportional to the tension or lack of same, responsive switch means for each device and actuatable by said portion at the limits of portion movement, a warning signal for each device and operable thereby and energizable by the second mentioned switch means at either limit of portion movement, and a single means in series with all of said second mentioned switch means and operable by any one of same for actuating said first mentioned switch means.

13. In a control system for knitting, coning and like machines having a driving motor and a brake, and switch means differentially controlling same, the combination of a single means controlling said switch means, a plurality of yarn tensioning devices, there being one for each yarn and having a portion movable proportional to the tension or lack of same, responsive switch means for each device and actuatable by said portion at the limits of portion movement, a warning signal for each device and operable thereby and energizable by the second mentioned switch means at either limit of portion movement, and a single means in series with all of said second mentioned switch means and operable by any one of same for actuating said first mentioned switch means, and an audible signal in multiple with the said single means and simultaneously operable therewith.

14. In a control system for knitting, coning and like machines having a driving motor and a brake, and switch means differentially controlling same, the combination of a single means controlling said switch means, a plurality of yarn tensioning devices, there being one for each yarn and having a portion movable proportional to the tension or lack of same, responsive switch means for each device and actuatable by said portion at the limits of portion movement, a warning signal for each device and operable thereby and energizable by the second mentioned switch means at either limit of portion movement, and a single means in series with all of said second mentioned switch means and operable by any one of same for actuating said first mentioned switch means, said single means comprising an electronic relay and an electronic tube.

15. In a control system for knitting, coning and

like machines having a driving motor and a brake, and switch means differentially controlling same, the combination of a single means controlling said switch means, a plurality of yarn tensioning devices, there being one for each yarn and having a portion movable proportional to the tension or lack of same, responsive switch means for each device and actuatable by said portion at the limits of portion movement, a warning signal for each device and operable thereby and energizable by the second mentioned switch means at either limit of portion movement, and a single means in series with all of said second mentioned switch means and operable by any one of same for actuating said first mentioned switch means, said single means comprising an electronic relay and an electronic tube, and an audible signal in multiple with the said single means and simultaneously operable therewith.

16. In a control system for knitting, coning and like machines having a driving motor and a brake, and switch means differentially controlling same, the combination of a single means controlling said switch means, a plurality of yarn tensioning devices, there being one for each yarn and having a portion movable proportional to the tension or lack of same, responsive switch means for each device and actuatable by said portion at the limits of portion movement, a warning signal for each device and operable thereby and energizable by the second mentioned switch means at either limit of portion movement, and a single means in series with all of said second mentioned switch means and operable by any one of same for actuating said first mentioned switch means and a visual signal in multiple with said single means.

17. In a control system for knitting, coning and like machine having a driving motor and a brake, and switch means differentially controlling same, the combination of a single means controlling said switch means, a plurality of yarn tensioning devices, there being one for each yarn and having a portion movable proportional to the tension or lack of same, responsive switch means for each device and actuatable by said portion at the limits of portion movement, a warning signal for each device and operable thereby and energizable by the second mentioned switch means at either limit of portion movement, and a single means in series with all of said second mentioned switch means and operable by any one of same for actuating said first mentioned switch means, said single means comprising an electronic relay and an electronic tube.

ROBERT N. AUBLE.
